BORE HOLE PUMP EQUIPMENT

Arthur Crawley Potter, Grantham, England

Application January 13, 1933, Serial No. 651,495
In Great Britain April 19, 1932

9 Claims. (Cl. 103—87)

This invention relates to bore hole pump equipments of the kind in which the pump and a motor for driving the pump are arranged in close association for introduction into the bore hole, 5 the motor being protected against the action of liquid within the bore hole by provision of an air chamber or diving bell whereby the liquid is prevented from encroaching upon the motor.

The invention has among its objects to provide 10 such an equipment that may be readily lowered into and raised out of the bore hole, and that may be either supported in position in the bore hole within the bore hole casing or the equivalent or suspended within the bore hole casing 15 from the ground level.

The invention has further among its objects to provide means whereby the air isolating the 20 motor may be controlled as to pressure for the determination of the level of water within the air chamber or diving bell and also to provide means whereby the pump may automatically be set into operation when the equipment is lowered to the desired position within the bore hole.

According to the invention the pump unit, comprising a centrifugal or other pump and an electric motor supported from the pump by an intermediate air chamber, is adapted readily to be lowered into or raised out of the bore hole and to be seated therein upon a water-tight seating. 30

According to the invention, moreover, the water-tight seating may be mounted within a tube serving as the rising main or within the casing of the bore hole or the equivalent.

According to the invention, moreover, the unit comprised by the pump equipment may be received upon a seating ring provided at the lower end of the tube which serves as a rising main, the pump body or the suction pipe of the pump extending through the seating ring, and ports 40 being provided to admit liquid from the exterior of the seating ring to the air chamber, while the pump delivery is provided to be in communication with the annular space surrounding the air chamber within the tube or rising main.

The invention has further among its objects to provide means for supplementing from the ground level the air in the air chamber of the pump equipment, which means are adapted to the particular construction of the pump equipment and the manner in which the said pump equipment is carried within the bore hole by the tube in which the seating ring is positioned. 50

The invention has also among its objects to provide a construction of seating ring which is adapted for adjustment of position within the

bore hole or shafting, to provide means whereby an electrically driven pump equipment may be supplied with current from contacts positioned upon the seating ring, to provide means to determine the accurate disposition of the pump equipment upon the seating ring for effective closure of the said supply contacts, to provide for the use of pump equipments according to the invention in series within the bore hole, and generally to provide improved pump equipments for use in 10 deep well and shaft pumping operations.

The invention further comprises the features hereinafter described and claimed.

The invention is diagrammatically illustrated by way of example in the accompanying drawings.

Figure 1 is a view in elevation of a submersible pump equipment constructed in accordance with the invention adapted for reception upon a seating in the rising main and having a water-tight 20 motor.

Figure 2 is a view in elevation of a submersible pump according to the invention, adapted for reception upon a seating in the rising main, the rising main being constructed with an air annulus or air ducts, for use in an unlined or partly 25 lined bore hole.

Figures 3, 4 and 5 are sectional views on an enlarged scale of alternative methods of constructing the rising main shown in Figure 2.

Figure 6 is a view in elevation of a submersible pump according to the invention, adapted for reception on a seating in the rising main, and having a water-tight motor, provision being made for supplying air from the well head to 35 the lower end of the air chamber by means of hose or other pipe connection.

Figure 7 represents in side elevation a pump equipment according to the invention, adapted for reception on a seating in the rising main, 40 and having the motor enclosed in an air chamber, provision being made for supplying air from the well head to the lower end of the air chamber by means of a hose or other pipe connection.

Figure 8 is a view in elevation of a submersible 45 pump equipment according to the invention mounted upon a seating of a construction adapted to fit within a bore hole casing or within a rising main at any determined position.

Figure 9 is a part sectional side elevation to an enlarged scale of the seating represented in Figure 8.

Figure 10 is a detail elevation of the lower end 50 of the pump equipment mounted in a rising main 55

provided with an extension closed by an automatically operated valve.

Figure 12 is a sectional elevation corresponding to Figure 11.

Figure 13 is a part sectional view of the rising main showing two modifications of construction 10 of the air passage.

Figure 14 is a part sectional elevation of a particular construction of seating ring for the pump equipment.

Figure 15 is a view in elevation and partly in 15 section of a pump equipment provided with a self-contained air compressor magnetically coupled to the motor shaft.

Figure 16 illustrates diagrammatically hydraulic control apparatus for regulating the operation 20 of the pump equipment.

Figure 17 shows a portion of the rising main and pump equipment for the purpose of illustrating means for supplying electric current to the motor without the use of cables from the 25 surface attached directly thereto.

Figure 18 is a detail plan view in section corresponding to Figure 17 taken on the line A—A of Figure 17.

Figure 19 is a detail plan view in section taken 30 on the line B—B of Figure 17.

Figure 20 illustrates a modification of certain parts illustrated in Figure 17.

Figure 21 is a sectional plan view taken on the line C—C of Figure 20.

Figure 22 illustrates a modified construction of 35 the rising main permitting of the passing of air downwardly through the rising main for transfer through passages in the pump equipment to the air chamber or diving bell.

Figure 23 illustrates the use of a plurality of 40 pumps disposed at different depths and operating in series, the pumps being suitably provided to operate upon gritty liquid.

Figure 24 is a plan view of the tubing shown 45 in Figure 23 together with the guides.

Figure 25 shows an arrangement of pump equipments provided in series within a common tubing or rising main.

Figure 26 shows an arrangement in which a 50 pump equipment is supported by a short length of tubing or rising main extending downwardly from a staging provided in the well or bore hole.

Figure 27 illustrates a construction of shaft bearing which may be used in pump equipments, 55 such as are represented in Figure 1, for the shaft connecting the motor and pump.

In carrying the invention into effect as illustrated in Figure 1 of the accompanying drawings, the equipment comprises the pump 1 and an electric motor 2 with water-tight casing, supported from the pump by an air chamber 3. In mounting the pump and motor equipment a tube 4 serving as a rising main is lowered down the bore hole and the equipment is lowered down to a water-tight seat within the said tube as at 5. The seating thus provided may be of any suitable form, and may, for example, comprise an inwardly directed transversely disposed flange suitably positioned in or at the end of the tube and a packing ring of resilient material provided upon the pump body, or it may, for example, be provided in the manner hereinafter described. The pump 1 is supported at its upper end upon the seating flange 5, while the electric motor 2 is supported from the pump by the casing or air

chamber 3 formed in sections which may be connected as at 6 by couplings adapted, if desired, to serve as bearings for the pump shaft with which the motor shaft is directly coupled. A thrust bearing 7 of any suitable type serving to 5 carry the weight of the rotating elements and to withstand the hydraulic thrust of the pump is advantageously provided at the upper end of the motor or at another suitable point above the uppermost liquid level, as illustrated, for example, in the modifications shown in Figures 8 and 9. Ports 8 are formed in the pump casing immediately below the seating flange or ring at 5 to convey leakage water from the upper pump stuffing box back to the suction side, or to admit a 15 fresh air supply to the air chamber 3, while the delivery of the pump is adapted to communicate with the interior of the tube 4 outside the pump equipment or air chamber 3.

The upper end of the rising main tube 4 is 20 supported by a suitable fitting 9 having the delivery 10, the fitting 9 being closed by a removable cover 11 which may be readily removed for raising or lowering the pump equipment by such means as a hoist. The design of the head fitting 9 is advantageously such that a definite pressure or head may be maintained within the rising main so that a booster pump may be supplied under pressure by way of the delivery 10.

Means are provided for supplying air or in- 30 creasing the pressure of air within the air chamber 3. For this purpose at the well head there is provided a compressor 12 with reservoirs 13 adapted to supply air by the piping 14 to the annular space 17, between the bore hole lining 35 and the rising main tube 4. Such an arrangement permits the water level in the annular space being lowered by air pressure until it reaches a level at which the air can enter by way of the ports 8 into the air chamber 3. Furthermore, 40 this arrangement permits the equipment to be submerged to relatively greater depths than would otherwise be the case without unduly increasing the capacity of the air chamber or alter- 45 natively to permit the use of a relatively small air chamber and thus a more compact construction of the pump unit or equipment.

As hereinbefore described, it is desirable that means should be available for depressing the 50 surface level of liquid within the bore hole by the introduction of air so that when the level of liquid has been depressed to a determined degree the air may freely pass into the air chamber or air bell by which the motor is protected. Thus, in cases where the air is introduced into 55 the bore hole between the rising main and the bore hole casing, difficulty is experienced if the bore hole casing does not extend to the level to which the level of liquid must be depressed, since there is a tendency for the air to escape into the earth or soil surrounding the bore hole. The same disadvantageous condition exists to a greater extent in circumstances where the bore hole is unlined.

For this purpose the rising main may be provided or constructed in various ways. Thus, the rising main may comprise two concentric tubes forming between them an annulus through which the supply of air may be passed. Again, the rising main may be formed with conduits or passages in the walls serving the purpose of a passage for the air to the air chamber or air bell. Again, suitable fittings providing a passage or conduit for the air may be applied in one or 70 more positions upon the inner or outer face of 75

the rising main; or again, the passage may be provided merely by a length or lengths of tubing, such as copper tubing, which may be carried downwardly either within or without the rising main.

It is necessary that, whatever the construction adopted, means shall be provided whereby at the junction between the succeeding lengths of rising main an effective joint between the air conduits or passages, fittings, tubes or the like may be made.

In Figure 2 of the accompanying drawings there is illustrated a construction of the rising main 4 such as that now described. It will be observed that the seating 5 for the pumping unit is carried from the inner of the concentric tubes forming the rising main and that the outer of the tubes extends below the said seating to ensure the passage of air which is passed into the annular space at the upper end of the concentric tubes and enters the air chamber through the ports 8.

In the preferred construction represented in Figure 3, the rising main is formed of concentric tubes 15, 16 the succeeding sections of the two tubes being suitably screwed together, the annular space 17 between the tubes serving as an air passage. The tubes may be provided with collars on the outside or nipples on the inner side or other suitable means of effecting the joints.

In the construction represented in Figure 4, the rising main is formed of concentric tubes 15, 16, the succeeding sections of the two tubes being connected by suitable ring connectors in which are provided communicating passages for connecting the annular space 17 between the upper concentric tube lengths with that of the succeeding concentric tube lengths. The ring connectors may be varied in construction according to requirements. Thus, they may comprise rings 18 of internal and external diameters corresponding respectively to the internal diameter of the inner tube 15 and the external diameter of the outer tube 16. Such ring connector is provided on the upper and lower surfaces with cylindrical walls 19 of suitable length which are screw-threaded on the inner and outer faces to engage respectively with screw threads provided upon the outer periphery of the inner tube 15 and the inner periphery of the outer tube 16. By such a construction a substantially uniform wall surface is given to the rising main on the outer and inner faces. The communicating passages 20 extending between the annular spaces 17 of the upper and lower tube lengths are formed as passages or conduits extending from the upper to the lower faces of the opposed cylindrical walls of the ring connector.

In the construction of ring connector represented in Figure 5, this is formed as a short cylinder 21 having an internal diameter approximating to that of the external diameter of the outer tube 16 and with a flange-like body 22 extending at the middle of the length and of a cross-section which is of considerable length in comparison with its thickness. The inner face 23 of the said flange is of a diameter to approximate to the exterior diameter of the inner tube 15 and is screw-threaded to engage screw threads provided upon the adjacent ends of the two lengths of the inner tube 15. The inner surfaces 24 of the cylinder which extend above and below the flange-like body 22 are also screw-threaded to engage screw threads provided upon the adjacent ends of the succeeding lengths of the outer tube 16.

The necessary passages 25 for communication between the upper and lower annular spaces 17 of the rising main are formed through the flange like body.

At the head of the bore hole, means are provided whereby a convenient connection of a source of air under pressure with the annular space 17 between the tubes of the rising main may be made. Thus, the tubes may at this position be connected to a connector 26 substantially as hereinbefore described, but provided with an outwardly extending flange 27 for its support from the casing 28 at the head of the bore hole, such connector being provided with no passages other than a single supply passage 29 which may conveniently pass either directly through to the upper surface or may be diverted through the flange 27 for connection to the supply pipe extending from a compressor or compressed air reservoirs. Other means may alternatively be employed such as a connection made to the annular space 17 between the tubes of the rising main through a boss 30 provided upon the wall of the outer tube 16.

While the construction hereinbefore described is preferred, other means may be adopted of forming the air supply conduit or passages for the purposes of the invention. Thus, there may be provided upon the inner or outer surface of the tube forming the rising main, as illustrated in Figures 11, 12 and 13, fittings 17a in which the necessary passages 17 are integrally formed or are formed between the said fittings and the surface of the rising main, and such fittings may be applied by welding or other means of mounting upon the rising main. At the junction between adjacent lengths of the rising main, suitable means may be provided for making joint between the adjacent fittings. Thus, the rising main tubes may, for example, be provided with annular projections 17b in which are formed in the end surfaces grooves or channels 17c which may form means of communication with the corresponding groove or channel of the succeeding length of rising main. Alternatively, tubing or piping 17d may be provided to form the air passage, and in such case the tube may be continuous or provided with joints corresponding to the joints in the rising main or otherwise disposed.

Communication may be made at the desired position between the air passages and the air chamber or air bell in any suitable manner. Thus, in the case of the concentric tubular formation of the rising main, this may be effected either by ports provided in the inner tube or by shortening of the inner tube in relation to the outer tube. Similarly, in the case of the use of fittings or tubing as hereinbefore described, ports 17e (Figure 12) may be provided in communication with the said fittings or tubes or the latter may be diverted to the inner side of the rising main.

In the construction represented in Figure 6 the arrangement is as hereinbefore described in Figure 1, but air is led from the compressor or reservoirs by way of hose pipe 31 within the rising main 4 to a fitting 32 at the lower end of the air chamber 3.

In the construction represented in Figure 7 the arrangement is as hereinbefore described in Figure 6, but the motor 2 is enclosed in an extension of the air chamber 3.

In pumping water having solid matter in suspension it is desirable that the passageways for the flow of the water from the impeller of the

pump to the head of the rising main should be substantially of similar cross-section to ensure an approximately uniform velocity of flow whereby the settlement of the solid matter may be avoided.

Figure 8 illustrates an equipment such as hereinbefore described mounted within the bore hole casing 35 by the use of a seating ring adapted to be fitted in a determined position within the bore hole casing.

In order that the pump may be so mounted, as shown in Figure 9, at any desired position in the bore hole casing 35 according to the construction represented in Figure 8 a tubular ring 36 is provided with means to permit the engagement or gripping of the surface of the casing which is formed of lengths of tubing 35 connected together by coupling sleeves 37. For this purpose the tubular ring 36 is provided on its outer periphery at the lower end with a plurality of dogs or wedge members 38 having a substantially dove-tail cross-section and disposed in circular series so as to slide in corresponding channels or slots 39 of a like cross-section formed in the external conical face of the lower portion of the tubular ring 36. The lower ends of the dogs or wedge members 38 project beyond the lower end of the tubular ring so that when a suitable tool adapted to engage the said ends of the dogs or wedge members is temporarily fixed or supported at a suitable position within the casing, the lower ends of the said dogs or wedge members come into engagement with the said tool when the tubular ring 36 is lowered into the casing and the dogs or wedge members are thus moved upwardly along their respective slides to function as wedges and by engagement of their serrated or roughened surfaces with the wall of the casing tightly to hold the tubular ring within the casing.

The upper ends of the wedge members 38 are adapted to contact with the under side of a metal ring 40 mounted around the tubular ring 36 in position beneath an externally applied massive packing ring 41 of rubber or other similar elastic material, above which a similar metal ring 42 is mounted around the tubular ring. The massive packing ring 41 is thus confined within an annular space so that on the wedge member 38 being displaced on the tubular ring 36 being set in position and the equipment being lowered into position upon it, the massive packing ring is so compressed and deformed as to make contact with pressure against the inner face of the casing 35.

Above the upper metal ring 42 a number of rings or turns of packing 43 advantageously of India rubber and of a substantially square, rectangular or other cross-section are set one above the other, the upper ring or turn lying beneath an overhanging flange 44 on a metal ring 45 upon which is supported the flange 46 of the pump equipment with the interposition of an elastic packing ring 47. By such or similar means the rings or turns of packing referred to are maintained under axial pressure and are pressed outwards to maintain a joint between the upper part of the tubular ring 36 and the casing 35 in position above the massive elastic packing ring 41. The pumping equipment may be lowered into position from the well head by means of non-twisting rope or chain, it being understood that the tubular ring may be similarly lowered into position by means of a non-twisting rope or chain from a suitable hoist. It will be understood that

the pump would thus be ready for operation on the electric motor being energized and that by so mounting the equipment leakage from the delivery side back to the suction side is precluded.

It may in certain cases be desirable suitably to form the inner wall of the casing for the support of the tubular ring at a determined position. For this purpose one of the coupling sleeves (Figure 14) may be provided on its inner face with an annular recess 31a of substantially saw-tooth cross-section so that an annular seating of shallow conical formation is provided that is adapted for the reception of a circular series of downwardly extending spring arms 38a respectively mounted upon the dogs or wedge members 38 and so formed that when their ends pass into the annular recess and the tubular ring continues to fall, the dogs or wedge members are caused to move along their slideways to engage the wall of the casing.

Ducts or ports 70 (Figure 8) are provided in the pump casing 1 to convey high pressure leakage water from the upper pump stuffing box back to the suction side.

In the use of a rising main such as 4, in order to facilitate the raising of the pump equipment from the bore hole, the rising main may be provided with an automatically operated valve opened when the pump equipment reaches its seating and closed when the pump equipment is withdrawn from the seating. Thus, as represented in Figure 10, the rising main 4 may be provided with an extension 48, which at the lower end, below the suction orifices of the pump 1, is provided with a closure fitting 49 having one or more openings 50 adapted to be closed by a valve 51. The valve 51 is supported by a stem or rod 52 which extends axially into the interior of the extension 48 and has mounted thereon a coiled spring 53 adapted to maintain the valve closed. The spindle or rod 52 extends inwardly sufficiently to be engaged by the suction fitting of the pump or a member carried thereby when the pump reaches the seating at 5. The arrangement is such that, on the pump equipment being lowered into position, the suction or inlet fitting of the pump engages the upper end of the valve rod or spindle 52 whereby under the weight of the pump the valve opens, while similarly when the pump equipment is raised the valve returns to its seat under the action of the spring 53.

Such a construction may be applied to any of the arrangements according to the invention provided with the rising main tube 4. It will be understood that in operation when the pump equipment is lowered and the valve opened, liquid enters the extension from the bore hole and the pump unit is ready for pumping. When the unit is raised from the rising main the valve closes, leaving the extension and the rising main charged with liquid. To expel the liquid compressed air may be admitted at the well head casing and the liquid thus forced out of the extension through the valve. When the supply of compressed air is cut off the valve again closes and is maintained closed not only by the spring 53, but also by the external water pressure.

Where desirable an air compressor with corresponding motor may be provided within the pump equipment at a suitable position and the operation of the compressor may be effected automatically in response to the variations in level of the float of a float-operated switch.

The air compressor may be operated, as indicated in Figure 15, from the main motor 2 through

a magnetic clutch 59a and controlled by automatic switch gear such as 69, as hereinbefore described.

It will further be understood that the operation 5 of the air compressor, whether situated at ground level or contained within the pumping unit may be controlled automatically by a time switch operated by a hydraulic control device or by a clock. Where a supply of alternating current is available 10 a clock of the type operated by a synchronous motor, the regulation of which is dependent upon the frequency of supply, may be used so that the control may continue so long as the supply of electric current is continued. Where it is desired 15 to employ a hydraulic control device, a controlled or adjustable leakage or flow of liquid a (Figure 16) may be delivered by a pivoted oscillatable chute b to a suspended receptacle c to fill the latter and cause downward movement under 20 gravity, which receptacle in its movement may effect the operation of the control switch d of the compressor motor. A second or similar receptacle e may serve in a similar manner to open the control switch d, such receptacle receiving 25 the leakage or flow of liquid by way of the pivoted oscillatable chute b, which is now thrown over to a second position. Thus, the plant may be left unattended and controlled from a power station at some distance, the air in the air chamber 3 being automatically renewed at regular intervals. 30

According to Figures 17 to 19 the electric supply cable 71 comprising three leads is carried downwardly on the exterior, or alternatively on 35 the interior, of the rising main 4 to which it is attached by such means as clips 72 welded to the rising main and is extended below the seating ring 5 where it is looped for connection to a terminal box 73 carried upon the lower surface of 40 the seating ring 5. The three leads are separated and disposed within a groove or channel 74 formed within the lower surface of the seating ring 5 and are by such means adapted to be connected respectively to three contacts 75 disposed 45 symmetrically in the seating ring 5 and extending upwardly through the upper surface. The said contacts may take any suitable form, but advantageously have their operative portions of wedge shape, the apex of the wedge being directed 50 upwardly from the seating ring, the thickness lying in the radial direction and the width in the circumferential direction with respect to the seating ring, and the width being of the order of two or three inches. A packing ring of rubber 76 or 55 other flexible and resilient material having the upper surface convex in the transverse direction may be provided upon the seating ring 5 with the contacts before referred to disposed in suitable recesses or slots therein.

60 The pump equipment is provided at the seating with a resilient packing ring 77 corresponding in form to the ring 76 of the seating ring 5, and in corresponding positions to those occupied by the contacts the pump equipment is provided with 65 spring fork-like contacts 78 disposed in recesses in the packing ring 77 in such manner that when the pump equipment comes to rest in the operative position with the packing ring 77 thereon lying upon the packing ring 76 of the seating ring 70 5, the spring contacts 78 engage the wedge contacts 75 to form an effective electrical connection. The contacts on the pump equipment are directly connected to the motor by insulated leads 79 extending upwardly through the pump and the air 75 chamber to the motor.

In order to ensure that the contacts provided respectively upon the seating ring and upon the pump equipment may come into effective and accurate engagement when the pump equipment is lowered into position, the pump equipment is 5 conveniently provided advantageously on the exterior of the motor casing 2 with ribs 80 which extend upon the two sides of the casing upon a plane inclined to the axis in such manner that the ribs meet in a point at the lower part of the 10 casing and after extending around the casing on opposite sides for a distance approximating to 180° continue parallel with the axis of the equipment at a determined distance apart. Such ribs are adapted to co-operate with an element or 15 elements 81 provided upon the interior of the rising main at a suitable position and of a form which extends in the radial direction to the degree necessary to ensure contact with one or other of the said ribs and finally to pass between 20 the said ribs where these extend parallel with the axis. The said element or elements may be in the form of a pin, stud or plate and may have a cross-sectional form presenting an upwardly directed point or inclined faces for suitable engagement with the rib or ribs upon the pump equipment. The motor casing may be provided at the upper end with one or more series of radially extending projections, plates, studs or pins 25 82, by which the pump equipment may be centered in the rising main 4.

It will be understood, however, that the ribs 80 may be alternatively provided, as illustrated in Figures 20 and 21, upon the interior of the rising main, and the co-operating element or elements 35 81 upon the pump equipment, the ribs 80 being advantageously disposed in a position immediately above the motor when the pump equipment is on the seating. The ribs may alternatively be disposed as a double helix 83, 84 (Figure 25) in which one rib is of quicker pitch than the other so that the ribs approach one another at those portions which are effective to guide the pump equipment immediately on to the seating ring, at which position the uppermost rib 83 may 45 end in such manner as to deliver the co-operating element 81 to the rib 84, the element 81 being constrained to follow the rib 84 by a rib or the like 85.

It will be understood that the width of the 50 pins or the like 81 corresponds substantially to the distance between the ribs 80 or 84, 85 at the position occupied by the pins or the like 81 when the pump equipment is upon or adjacent the seating ring so that by the engagement of the said 55 co-operating elements 81 with the ribs the pump equipment is guided downwardly in the direction necessary to bring the contacts 78 thereon effectively into engagement with those upon the seating ring 5. The concentricity of the pump 60 with the seating ring is conveniently secured by the ribs or plates 82 upon the interior of the rising main or upon the pump equipment.

The rising main may be provided on the exterior adjacent the seating ring with a shield 65 or casing 86 (Figure 17) for the protection of the downwardly looping cable 71 leading to the terminal box 73.

In an alternative construction of the packing 70 between the seating ring and the pump equipment, as illustrated in Figure 20, the packing may be formed by a single ring 87 carried by the pump equipment, the lower surface of which ring is convex in the transverse direction and is adapted to rest upon the ground or machined 75

face of the seating ring 5. Thus, as the pump equipment descends on to the seating, the middle of the section of the packing ring first makes contact with the seating ring and water is pressed outwardly on each side so that an effective joint and seating is secured upon the seating ring.

In order to permit the air in the air casing or diving bell to be supplemented the rising main 4 10 may be extended downwardly below the seating ring 5 (Figure 22) to surround the greater part of the pump equipment. Air passages 88 may be provided in the pump casing extending from the suction side of the pump at a position below the 15 seating ring to the air casing. Thus, when it is required to introduce air into the air casing or diving bell, the operation of the pump is arrested and air is forced downwardly under pressure in the rising main. The level of water is in this 20 manner caused first to fall to the suction level and then to be depressed below the seating ring until the openings to the air passages in the pump casing are exposed, when the air passes freely into the air casing. This feature of the 25 invention may be applied in connection with pump equipments which are not provided with the means for the supply of current in the manner hereinbefore described.

In the application of the invention to pump 30 equipments for use in mines and for like purposes, where liquid charged with grit or sediment is present, as illustrated, for example, in Figure 23, the tubing 4 provided as hereinbefore described with a seating ring 5 upon which the 35 pump equipment rests is also provided with an auxiliary seating ring 89 disposed at a distance above the main seating ring for co-operation with a seating flange 90, lined with packing, provided upon the pump equipment at a suitable position 40 above the main seating, the auxiliary seating ring having an opening larger than that of the main seating ring to permit the portion of the pump equipment which is received upon the main seating ring to pass through it. The tubing 4 at a 45 position intermediate the main and auxiliary seating rings is provided with a delivery opening 91 making communication with a delivery tube 92 of relatively small diameter which extends upwardly in a position adjacent the tubing. Where 50 desirable the delivery tube may be multiplied (as shown to the right of Figure 23) and the delivery from the pump may be effected into an annulus corresponding to the opening 91, surrounding the tubing with which the tubes 92 are connected.

According to the depth of the main it may be 55 advantageous to employ a plurality of pump equipments operating in series. In this case, as illustrated in Figure 23, at the lowest section of 60 the shaft there may be arranged upon a suitable supporting platform 93 and extending along the shaft a plurality of longitudinal members 94 (Figure 24) serving as slides or fitted with rails 95 for supporting, through runners 96, the downwardly extending tubing 4 provided with the main and auxiliary seatings 5 and 89 for the pump equipment and the delivery tube 92 of small diameter extending upwardly along the tubing 4 and provided with several delivery branches 97 65 having flanged connections, suitably closed when not in use by closure plates 98, screwed coupling sockets adapted to receive screwed closure caps, or being otherwise provided to afford delivery outlets at suitable positions. The tubing 4, with 70 75 the pump equipment therein, is suitably slung

in such manner that it may be lowered in the shaft as required upon the members 94. The pump equipment disposed next above is supported upon the platform 93 or another platform or from the ground level but in a position which is out of line with the axis of the tubing 4 supporting the lowermost pump equipment. The second pump equipment is similarly supported in its tubing upon main and auxiliary seatings which form the delivery chamber of the pump equipment for communication with a delivery tube of small diameter, but in this case the tubing is extended below the main seating 5 to connect with a suction fitting 99 comprising a casing of cylindrical or other form fitted at the lower end 10 and formed or fitted with a valve 100 and couplings 101 and 102 for connection on the one hand to the suction of the second pump equipment and on the other hand for connection to the delivery branch 97 of the delivery tube 92 20 of the lowermost pump equipment which is most conveniently positioned, advantageously by means of a flexible tubing 103 or other tubing of adjustable length permitting of the lowering of the first pump equipment and its supporting tube 25 upon the rails 95 as the well or shaft is deepened. The same arrangement of pump equipments may be provided for use in pumping liquids which are not gritty. In this case, however, the duplex seatings are not required and the delivery from 30 the rising main of the lowermost pump equipment will be effected to the suction fitting of the succeeding pump equipment. Alternatively, as illustrated in Figure 25, a plurality of pump equipments may be arranged in series within the same 35 tubing or rising main, on seating rings 5 in the manner before described and the tubing within which they are carried may serve as the rising main for each pump equipment. The supply of electric current may be effected by means of cables 71 extending downwardly along or upon the rising main and adapted to make electrical connection at the seating rings 5 with the respective pump equipments in the manner before described. It will be understood that in the case of the 40 mounting of a series of pump equipments in the same tube the seating rings of the upper pump equipments must have a diameter of opening sufficient to permit the passage of the lower pump equipments, and that where it is desired to adjust, inspect or repair the lowermost pump equipment it is necessary to remove the upper pump equipments before the lowermost pump equipment can be withdrawn, the latter being the first to be 45 replaced in position.

It will be obvious that in this series arrangement of the pump equipment, again, the duplex seating and delivery tubes may be provided and the upper pump equipment may have suction 50 fittings which may form part of the pump equipment and be provided to be received on a seating in the tubing in such position as to make the necessary connection with the delivery tubing of the lower pump equipment.

Where the conditions of use of the pump equipment are such that it is possible to support the pump equipment from a staging or platform disposed at a level below the ground surface, as represented in Figure 26, the rising main or tubing 4 supporting the pump equipment may be shortened and thus rendered less costly by the provision of a staging 104 at a position immediately above the highest rest water level and by the provision upon the staging of the head fitting 11 for the rising main so that the latter extends 75

downwardly from the staging only through a comparatively short distance. The delivery 10 from the head fitting is then carried upwardly within the shaft or well.

- 5 Those arrangements of the pump equipment, in which the delivery is effected by way of a delivery tube of small diameter from a delivery chamber formed between two seatings and in which the tubing supporting the pump equipment 10 serves merely for that purpose, are specially advantageous for use in such situations as in mines where it is desired frequently or periodically to inspect the pump equipment or the motors driving the pumps without the necessity for lifting 15 the equipments to the surface, since the tubing within which the pump equipment is supported may, as shown in Figure 23, be provided with inspection doors 105 by which access may be had through inspection openings to the pump equipment while it is in position whereby, for example, the adjustment of the brushes of a direct current motor or the slip rings of an alternating current motor may receive attention by 20 way of a manhole or manholes provided in the casing of the motor.

It will be understood that the invention is not limited to the details of construction that are hereinbefore set forth. For example, the supply cables may be carried on the interior of the rising 30 main instead of on the exterior. Again, the bearing which is formed in the coupling members 6 of the air casing 3 for the shafting between the pump 1 and the motor 2, as described with reference to Figure 1, may be provided as a water 35 lubricated bearing. For this purpose, water may be supplied to the bearing in the manner that is indicated in Figure 27. A copper or like tube 106 is mounted within the air casing to extend from the pump delivery to 107 to a position above the bearing where it is bent or diverted to give 40 a downward discharge of the water forced through it by the pump into a trough 108 above the bearing and around the shaft, whereby the water is permitted to travel through the bearing 45 and finally to pass away by the leakage passages 8 that are already present and which are large enough to deal with the small quantity of high pressure water that is introduced from the pump delivery.

- 50 The pump may be provided with an upright laterally disposed pump delivery or trunk represented by the cross-sectional passage at the one side and extending to the motor jacket and communicating with a corresponding vertical passage 55 in the air casing or bell and with a central upwardly extending rising main upon or above the bell while an upright laterally disposed air trunk, as represented by the second of the cross-sectional passages, may be provided opposite to the 60 upright laterally disposed delivery or trunk. These respective trunks may serve as the support for the air casing or bell. The air trunk may be so formed as to communicate with the central space in the air casing or bell which for the purpose 65 may be closed at its lower end, there being free communication between the air trunk and the chamber in the bell casing above and also through the casing of the pump in communication with the space in the bore of the downwardly extended part of the special tube or of the extension. Or the pump casing, the bell casing and the intermediate chamber between the pump casing 70 and the bell casing for the motor may be provided of a double wall, and one part may be 75 adapted by means of integral partitions to serve

for the pump delivery and the other as the air trunk communicating with the chamber within the top of the bell casing. Or again, the pump delivery may be accommodated at one side of the air chamber and bell casing.

5 It will also be understood that the well head may be provided with a head fitting 11 such that the electric cables and other parts may pass through the tight glands, or be otherwise held within the head fitting. The closure may be provided to break the circuit to the motor by operation of a suitable switch when it is moved into the open position.

10 It will furthermore be understood that the construction represented in Figures 9 and 14 may be variously modified as, for example, with respect to the means employed to secure tight joints between the tubular ring and the casing and between the tubular ring (or the seating ring 5 when employed) and the lower part of the pump equipment, and for locating the tubular ring within the casing or within the special tube when employed.

15 I claim:—

1. Bore hole pump equipments, comprising a pump and submersible driving motor, the said motor being supported from the pump by an intermediate air chamber, with tubing for reception into the bore hole and into which the equipment may be lowered, a seating member carried by and within said tubing and upon which said equipment may be removably positioned, and passages in the pump equipment opening below the level of the seating member and connecting with the air chamber for the passage to the air chamber 30 of air passed downwardly from the ground level.

2. Bore hole pump equipments, comprising a pump and submersible driving motor, the motor being supported from the pump by an intermediate air chamber, with tubing adapted to be received into the bore hole and to receive the pump equipment, a seating member carried by and extending into the said tubing, upon which the pump equipment is removably positioned, and means for supplementing the air within the air 40 chamber from the ground level by way of the tubing, the latter being formed of two concentric tubes the annular space between which serves as a longitudinal passage for the air supplied from ground level to the air chamber.

3. Bore hole pump equipments, comprising a pump and associated motor with an air chamber for said motor, with tubing for insertion into the bore hole for the reception of said pump equipment, a seating for said pump equipment at a determined position within said tubing, electric supply cables extending down said tubing to said seating, contacts in electrical communication with said cables and supported in proximity to said seating, and corresponding contacts upon the pump equipment in electrical connection with the motor, which contacts are adapted to engage the contacts connected to the supply cables when the pump equipment rests upon the seating.

4. Bore hole pump equipments according to 55 claim 3, having co-operating means provided respectively upon the pump equipment and upon the tubing carrying the seating for the pump equipment, whereby the pump equipment is lowered on to the seating with the electrical contacts 60 in determined engagement.

5. Bore hole pump equipments, comprising a pump and associated motor with an air chamber for said motor, with tubing for insertion into a 70 shaft, spaced seatings at a determined position 75

- within said tubing to receive said pump equipment, said spaced seatings providing a delivery chamber for the pump, and tubing by which the liquid from the said delivery chamber is discharged upwardly. 5
6. Bore hole pump equipments according to claim 5, comprising a plurality of pump equipments and supporting tubes disposed out of alignment within a shaft, each supporting tube 10 being provided with upwardly directed delivery tubing, and a suction fitting upon the intermediate and upper supporting tubings for connecting the suction of the corresponding pump equipments with the delivery tubing of the lower 15 pump equipment.
7. Bore hole pump equipments according to claim 5, comprising a plurality of pump equipments and supporting tubes disposed out of alignment within a shaft, each supporting tube 20 being provided with upwardly directed delivery tubing, a suction fitting upon the intermediate and upper supporting tubings for connecting the suction of the corresponding pump equipments with the delivery tubing of the lower pump 25 equipment, longitudinal guides for the supporting tube of the lower pump equipment, whereby it may be moved axially, and means for connecting the suction fitting of the supporting tube of the succeeding pump equipment at determined 30 positions to the delivery tubing of the lowermost pump equipment.
8. Bore hole pump equipments, comprising a pump and submersible driving motor, said motor being supported from said pump by an intermediate air chamber, with tubing for insertion 35 into the bore hole within which the said pump equipment is adapted to be received, an annular seating member carried by and extending inwardly of said tubing, said seating member removably supporting the pump equipment by engagement with a seating upon the pump equipment intermediate the length thereof, without mechanical connection with the ground level, means at the ground level for the supply of compressed air, the said air being passed downwardly at the exterior of the tubing, and 40 passages in the pump equipment extending from below the seating of the air chamber, said passages serving to permit the compressed air to pass to the air chamber.

ARTHUR CRAWLEY POTTER. 40
